(57) **CLAIM**

The ornamental design for a human information sensor, as shown and described.

DESCRIPTION

FIG. 1 is a front perspective view of a human information sensor;

FIG. 2 is a rear perspective view thereof;

FIG. 3 is a front elevational view thereof;

FIG. 4 is a rear elevational view thereof

FIG. 5 is a left side view thereof;

FIG. 6 is a right side view thereof;

FIG. 7 is a top plan view thereof; and,

FIG. 8 is a bottom plan view thereof.

The broken lines depict environmental subject matter only and form no part of the claimed design.

The oblique short lines in FIGS. 1 and 3 are intended to illustrate that the surface is translucent.
